FOLDABLE BALANCED LAMP

Albert C. Perbal, 801 S. Skinker St.,
St. Louis, Mo. 63105

Filed Apr. 11, 1966, Ser. No. 1,849

Term of patent 14 years

(Cl. D48—20)

FIG.1

I claim:

The ornamental design for a foldable balanced lamp, substantially as shown and described.
